UNITED STATES PATENT OFFICE.

ANTONIO ABIZAID, OF DOUMA, SYRIA, TURKEY.

FRICITION-SLIDE FOR GARMENT-SUPPORTERS.

No. 821,611.

Specification of Letters Patent.

Patented May 22, 1906.

Application filed January 16, 1906. Serial No. 205,375.

To all whom it may concern:

Be it known that I, ANTONIO ABIZAID, a subject of the Sultan of Turkey, whose legal residence is Douma, district of Botroun, 5 Mount Lebanon, Syria, Turkey, have invented new and useful Improvements in Friction-Slides for Garment-Supporters, of which the following is a specification:

My present invention relates to certain 10 new and useful improvements in what are known in the art as "friction-slides for garment-supporters"—such, for instance, as used in holding the webbing of suspenders, stocking-supporters, and the like.

The objects of the invention are generally 15 to provide a friction-slide that will be simple in construction, inexpensive to manufacture, and efficient and reliable in operation.

Briefly and generally stated, the invention 20 comprises a frame which is preferably, but not necessarily, stamped from a single piece of sheet metal and embodying in its construction a central friction holding-bar and two parallel outer bars connected by integral 25 end pieces with said central bar, each of said outer bars being formed with an outwardly-extending offset portion for a purpose presently to appear.

The invention further comprises a slide of 30 the character described in which the central bar is provided with integral lips or tongues that are folded back upon the body of the bar and constitute the attaching means for securing the slide to the end of the webbing of 35 the suspender or other garment-supporter.

In order to enable others to clearly understand and appreciate the invention and its objects, I will now proceed to describe the same in detail, reference being had for this 40 purpose to the accompanying drawings, in which—

Figure 1 is a front view of a suspender-end having my improved slide applied thereto. Fig. 2 is an edge view of the same, showing the slide in section. Fig. 3 is a detail view of the slide. Fig. 4 is a perspective view looking at the rear side of a slide having integral means associated with the central bar for clamping the webbing of the supporter; and 50 Fig. 5 is a section of the same, showing the manner of attaching webbing thereto.

Referring to the drawings, the reference- 55 numeral 1 designates the usual webbing of a suspender-end, which carries any ordinary form of metal or other loop 2, from which the

end straps 3 are suspended, these parts being of any well-known construction.

The improved friction-slide is preferably stamped as a single piece from sheet metal and consists of a central friction holding-bar 60 4, two end pieces 5, and two outer bars 6, which lie parallel with the central bar. Each of the outer bars 6 is formed intermediate its ends with an outwardly-extending offset portion 7, which is of less length than the bar itself and to each of which is attached a short tab 8 to facilitate the adjustment of the slide. By the arrangement shown and described it will be seen that the friction-slide is provided with two parallel slots spaced apart 70 by a central friction holding-bar and that each slot has an offset tab-receiving portion. By forming the outer bars 6 with offsets 7 in the manner described no separate tab-supporting members are necessary, as is the case 75 with some other forms of slides, and I thus save material and reduce to a minimum the cost of manufacture of the slide. In addition to this, that portion of each tab 8 that is looped about its offset 7 is brought into frictional engagement with those portions of the webbing 1 that are passed between the outer bars 6 and central bar 4, and this frictional engagement of the tabs with the webbing insures a tighter grip of the slide and prevents 80 accidental slipping.

In the form of device shown in Figs. 1, 2, and 3 the end of the webbing 1 is looped about the central bar 4 and sewed; but in Figs. 4 and 5 I have shown a construction 90 wherein this sewing is entirely dispensed with. In these figures the slide is formed precisely as that form shown in Figs. 1, 2, and 3, except that instead of entirely cutting out the metal between the central bar 4 and 95 two outer bars 6, as in the first form, these metal lip portions, which are designated by the numeral 9, are left attached to the central bar 10, as shown in Figs. 4 and 5, and they are then bent or folded back to constitute the attaching means for the end of the webbing. In attaching the webbing one of the metal lip portions 9 is first bent or folded back upon the end of the webbing 1, which has been previously laid upon the rear side of 100 the bar 10. The webbing is then folded or turned down, as shown, and the other lip portion 9 is then folded over the webbing and over the lip portion, and the parts are then firmly pressed, so as to securely clamp the 105 slide.

webbing. This manner of attaching the webbing does away entirely with sewing, and as the lip portions are formed from the necessary stamping operation in the manufacture of the slide it will be apparent that the cost of the device is not added to by the construction described.

Having thus described my invention, what I claim as new, and desire to secure by Letters Patent, is—

1. A friction-slide of the character described, having two parallel slots spaced apart to form between them a central friction holding-bar and each slot having an offset tab-receiving portion.

2. A garment-supporting web having associated therewith a friction-slide, formed from a single piece of material and embodying a central bar having rearwardly folded and overlapped lip portions between which and said central bar an end of the web is clamped, and two outer bars arranged parallel with the central bar, each outer bar having a tab-receiving offset portion of less length than its bar, and a tab looped about each offset por-

tion, the looped portions of the tabs being in close surface contact with the supporting web at the points where the web passes over the central bar whereby to increase the frictional resistance of the web at such points. 30

3. A garment-supporting web having associated therewith a friction-slide formed from a single piece of material and embodying a central bar and two outer bars arranged parallel therewith, each outer bar having a tab-receiving offset portion of less length than its bar, and a tab looped about each offset portion, the looped portions of the tabs being in frictional contact with the surface of the web at the points where the web passes over the central bar, whereby to increase the frictional resistance of the web at these points. 40

In testimony whereof I have hereunto set my hand in presence of two subscribing witnesses.

ANTONIO ABIZAID.
